UNITED STATES PATENT OFFICE.

HARRY R. NOFTZ AND FREDRICK J. SCHWIMMER, OF TOLEDO, OHIO.

COMBINED ROTARY EARTH-BORING AND DRAW MACHINE.

1,312,565.

Specification of Letters Patent. Patented Aug. 12, 1919.

Application filed January 13, 1919. Serial No. 270,908.

To all whom it may concern:

Be it known that we, HARRY R. NOFTZ and FREDRICK J. SCHWIMMER, citizens of the United States, and residents of Toledo, in the county of Lucas and State of Ohio, have invented a certain new and useful Combined Rotary Earth-Boring and Draw Machine; and we do hereby declare the following to be a full, clear, and exact description of the invention, such as will enable others skilled in the art to which it appertains to make and use the same, reference being had to the accompanying drawing, and to the characters of reference marked thereon, which form a part of this specification.

This invention relates particularly to boring machines of the well drilling type in which a rotary pipe or drill spindle is driven to impart a rotary movement to the attached drill tool, and at the same time is permitted to lower in the well or hole drilled as the drilling progresses.

It has been customary in the use of machines of this character to employ what is termed a "draw works" to raise or withdraw the rotary pipe, which is made up of a plurality of sections or lengths coupled together, from the well, and this "draw works," so far as we are aware, has comprised a unit which is separate from and independent of the boring machine.

The primary object of our invention is to combine a boring machine of the rotary type and a draw works in a unitary structure, which is simple in its construction, efficient in its operation and compact in its arrangement of parts, thereby enhancing the practicability and commercial value of machines of this character and effecting an economy in the construction thereof.

Further objects of our invention are the provision of an improved form of driving chuck for the rotary pipe or drill; the provision of a simple and efficient unitary control for the various control clutches of the machine; and the provision of a simple and efficient mechanism, which is operable to drive either the boring means or the draw means, as desired. Further objects and advantages of the invention will be apparent from the following detailed description thereof.

While the invention in its broader aspect is capable of embodiment in numerous forms, a preferred embodiment thereof is illus-

trated in the accompanying drawings, in which,—

Figure 1 is an elevation of the same in operative association with a well derrick and with parts of the latter broken away. Fig. 2 is a plan view of the machine embodying the invention with parts removed and broken away. Fig. 3 is a central vertical section thereof on the line 3, 3 in Fig. 2. Fig. 4 is a side elevation thereof. Figs. 5 and 6 are a fragmentary plan and a fragmentary side elevation of the machine with parts removed. Figs. 7 and 8 are enlarged central vertical sections of the filler ring and driving chuck taken on the lines 7, 7 and 8, 8, respectively, in Fig. 9, and in operative engagement with a rotary pipe. Fig. 9 is a plan view thereof. Fig. 10 is a perspective view of the filler ring with the chuck removed. Fig. 11 is a central vertical section of the filler ring and rotary pipe chuck taken on the line 11, 11 in Fig. 12, and with one member of the rotary pipe clamp in position thereon. Fig. 12 is a top plan view of the filler ring, with the rotary pipe clamp mounted thereon and in engagement with a pipe, and Fig. 13 is a perspective view of one of the members of the rotary pipe clamp.

Referring to the drawings, 1 designates the base frame of a machine embodying the invention, which is mounted, in the present instance, on runners or skids 2, 2, and is provided at its central portion with a hollow vertical journal 3, the opening 4 of which extends entirely therethrough and is open at its top and bottom to permit the lowering of a rotary drill-carrying pipe or spindle 5 therethrough.

A sleeve or hub 6, forming, what may be termed, a "rotary driver" or "driver-sleeve" is mounted for free rotation on the journal 3 and has its upper portion extended above and shouldered over the upper end of the journal at 7, in end thrust bearing contact therewith to support the sleeve in proper position on the journal. The upper end of this sleeve may be provided with wrench sockets 8 to facilitate a hand turning thereof. A filler-ring 9, which, in the present instance, is substantially square in form and is intended to carry the rotary pipe-chuck 10, is set into a correspondingly shaped socket provided therefor in the upper end of the driver-sleeve 6 and is caused to have rotation with said sleeve.

The driver-sleeve 6 is provided at its lower

end with an annular set of teeth forming a beveled gear 11 concentric to the sleeve axis and in mesh with a beveled drive pinion 12, loose on a horizontal drive shaft 13, which 5 is suitably journaled in the base frame, as hereinafter described, and connected to any suitable source of power. A clutch sleeve 14 is splined on the shaft 13 and movable into and out of clutch engagement with the 10 pinion 12.

The draw means employed for hoisting or drawing the rotary pipe or spindle 5 from the well being bored, comprises a drum 15, which is sleeved or journaled on the driver-sleeve 6 for free rotary movements thereon and has a bearing support at its lower end at 16 on the shoulder formed on the driver-sleeve by the gear 11. The drum 15 is also provided at its upper end with an annular 15 flange 17, which overhangs and interengages with the upper end of the driver-sleeve 6. The drum 15 has the outwardly extending upper and lower flanges 18 and 19 between which the draw-cable 20 winds on the drum, 20 and the lower flange 19 is provided on its under side with two radially spaced beveled gears 21 and 22, which are without and concentric to the gear 11 on the driver-sleeve, with the teeth of the former more remote 25 from the shaft 13 than those of the latter, so that one acts as a high and the other as a low speed gear for the drum.

Drive pinions 23 and 24 of different sizes, which are loose on the shaft 13, mesh, respectively, with the gears 21 and 22. The clutch 14 is disposed intermediate the pinions 12 and 23 and may be moved to place either pinion in driving connection with the shaft 13. The pinion 24 has its hub elongated and extended outwardly through a bearing box 25 of the split type, and its outer end is adapted to be engaged by a clutch sleeve 26 splined on the shaft 13. It is thus evident that either pinion 23 or 24 40 may be connected to the drive shaft and cause a relative fast or slow driving of the draw drum 15, and that the clutch sleeve 14 may be moved to disengage the pinion 23 and engage the pinion 12 to impart a driving action to the driver sleeve 6 and a consequent rotary drilling movement to the rotary pipe or drill spindle 5. The drum 15 is provided in the top of its upper flange 18 with wrench sockets 27 to facilitate a hand 45 turning of the drum.

Shipper-levers 28 and 29 are provided, respectively, for the clutch sleeves 14 and 26, extending horizontally therefrom and being fulcrumed to respective frame brackets 50 60 and 31. The shipper-lever 28 has a bar 32 projecting outwardly from its outer end substantially in parallel relation to the shaft 13 and the lever 29 has a similar bar 32 projecting inwardly from its outer end in the plane 65 of projection of the bar 32, and, in the pres-

ent instance, below the same in vertically spaced relation thereto, as best shown in Fig. 6. A control-lever 34 is fulcrumed in vertical position to a bracket 35 rising from the base frame 1 at the outer side of the bars 32 and 33, and this lever carries a dog 36 at its lower end for vertical rocking movements intermediate the bars 32 and 33. This dog is provided at one end with upper and lower catch lugs in position to be swung respectively into interlocking engagement with registering notches 37 and 38 in the adjacent edges of the respective bars 32 and 33. A hand latch 39 is pivoted to the upper end portion of the control lever 34 and has a 70 rod 40 extending downward therefrom to one end of the dog 36, whereby rocking movements of the latch 39 will throw the dog into engagement with a coacting notch in one or the other of the bars 32, 33. In 75 the present instance, the latch 39 is normally held in its outwardly swung position with respect to the lever, and when in such position the upper lug on the dog 36 is in engagement with the notch 37 in the bar 32, 80 and an inward swinging movement of the latch from this position will cause a rocking of the dog 36 to release its engagement with the bar 32 and cause its lower lug to engage the notch 38 in the bar 33. It is thus apparent that when the dog 36 is interengaged with the bar 32, a movement of the control-lever 34 will effect a shifting of the clutch sleeve 14 in one direction or the other to engage or release either of the associated 85 pinions 12 and 23, and that a swinging movement of the control lever when the dog 36 is interengaged with the bar 33 will cause a shifting of the clutch sleeve 26 into and out of clutch engagement with the pinion 24. It 90 is apparent with this arrangement that only one of the bars 32, 33 can be shifted at one time by a movement of the control lever 34, thus insuring against throwing one of the 95 clutches into engagement with a draw drum 100 driving pinion when the drive pinion 12 is in clutch engagement with the shaft. A trip-rod 41 is carried by the upper end portion of the control-lever 34 for longitudinal movements lengthwise thereof, and has a 105 shoulder 42, which, when the catch 39 is drawn a sufficient distance toward the lever to place the dog 36 in operating engagement with the bar 33, moves into position to engage a lug or finger 39^a on the lower end of 110 the catch 39 and to retain the catch in said position. A spring 43 encircles a portion of the trip rod and acts against the shoulder 42 thereon to normally urge a movement of such shoulder into position to retain the 115 latch 39 in its retracted position relative to the lever. The outer end of the trip rod 41 extends without the upper end of the control lever in position to be depressed by the 120 thumb of the hand of the operator grasping 125 130

the lever so as to move the shoulder 42 on the lug out of holding engagement with the catch 39.

A split brake-band 44 encircles the peripheral portion of the lower flange 19 of the draw-drum in position to have binding engagement therewith, and in the present instance, comprises two sections which are pivoted at adjacent ends to a common pivot 45, rising from the base frame 1 at one side of the drum, and the opposite ends of the said sections are connected by a draw-rod 46, which extends loosely through lugs 47 on the free ends of said sections and carries a coiled compression spring 48 between said lugs in outward thrust contact with each to normally exert an outward drum releasing movement to the sections. A brake-lever 49 is fulcrumed to one of the lugs 47 and has a toggle-link connection 50 with the rod 46 at the outer side of such lug; whereby a rocking of the brake-lever in one direction will effect a relative inward movement of the free or connected ends of the brake-band and a consequent tightening of the band against the drum periphery.

For convenience in assembling, the drive-shaft 13 and parts carried thereby are suspended beneath the base frame 1, the bearing box 25 being suspended from an arched end portion or cross-beam 51 of the frame 1 by bolts 52, which bolts also serve to secure the sections of the bearing box together. The inner end of the shaft 13 is supported by a bearing box 53, which engages over the extended hub portion of the pinion 12 and is suspended from the under side of the base frame by bolts 54 (Fig. 5). It is thus evident that the shaft 13, pinions 12, 23 and 24 and clutch sleeves 14 and 26 carried thereby and the bearing boxes 25 and 53 may be removed as a unit from the machine by simply removing the suspending bolts 52 and 54.

The filler-ring 9 is loosely inserted into a receiving socket or recess 55 in the upper end portion of the driver-sleeve 6, one having shouldered engagement with the other to limit the movement of the filler ring within the sleeve and the two being of such complementary cross-sectional shape that one is driven by the other, and in the present instance, the socket 55 and filler ring are substantially square in form. The bottom of the socket 55 is open to the opening 4 through the journal 3. The filler ring 9 is provided centrally in its top with a recess or socket 56 for receiving the rotary pipe-chuck 10, and the central portion of the bottom of the recess 56 is provided with an opening 57 (Figs. 3 and 11) to permit the free passage of the rotary pipe or drill spindle 5 therethrough. While the chuck 10 may be of any of the forms commonly used for the purpose, the embodiment thereof

illustrated comprises a member 58 adapted to fit into the filler ring recess 56 and to turn with said ring and having a central vertical opening therethrough, the wall of which is provided with a plurality of cam surfaces 59 successively arranged therearound, as illustrated in Fig. 9. A chuck roller is disposed between each cam surface 59 and the rotary pipe 5, whereby a turning of the filler ring in clockwise or pipe driving direction 75 will cause a rolling of the chuck rollers toward the ends of the cam surfaces which are closest to the pipe axis and a consequent driving chuck engagement of the rollers with the pipe. These rollers are preferably arranged in pairs with the members thereof at opposite sides of the rotary pipe and with the rollers of one pair shorter vertically than those of the other pair. The long rollers are designated 60 and the short rollers are 80 designated 61. The purpose of varying the lengths of the chuck rollers of the two pairs is to enable the rotary pipe to be gripped and held by one pair when the other pair is released therefrom to permit 90 the enlarged coupling 5^a of the two pipe sections to pass down between the same. In other words, when the lower end of a coupling 5^a has lowered substantially into coaction with the upper ends of the rollers of 95 the longer set, such rollers may be moved outward a sufficient distance to permit the coupling to pass downward therebetween while the rollers of the shorter set are still in driving engagement with the pipe. The 100 same action takes place when the coupling has lowered substantially into position for its lower end to engage the tops of the shorter rollers, as such rollers may then be withdrawn to permit the coupling end to 105 pass downward therebetween. During this action the longer rollers are in driving engagement with the coupling. The rollers are retained in assembled position within the member 58 by pintles 62, which project 110 through enlarged axial openings in the rollers and have their lower ends loosely projecting into respective cam grooves 63 in the bottom of the filler-ring socket 56, while the upper ends of said pintles project upward through similar cam slots 64 in the plate 65 secured to the top of the member 58. The member 58 has recesses 66 therein at the outer end of each cam surface 59 into which the respective clutch rollers may move 115 when in released or neutral position relative to the rotary pipe.

The customary pipe clamping members 67, 68 are mounted on the top of the filler ring 9 with their ends provided with inclined outer side surfaces 68, which fit between correspondingly inclined surfaces 69 on lugs 70, which rise from the corner portions of the filler-ring, as well understood in the art. It is thus evident that tapered sur- 130

faces 69 on the filler-ring will coöperate with the clamping members 67 to cause said members to grip the pipe 5 in opposing relation when said members are lowered between 5 said tapered surfaces. The clamping members 67 are provided with hardened pipe gripping inserts 71.

In Fig. 1, 72 designates a derrick frame which is mounted over the well being bored, 10 and the draw cable 20 is illustrated as passing from the drum 15 under a sheave 73, carried by the derrick frame at one side thereof, and thence up to the top of the derrick over a sheave 74 and down therefrom to the upper 15 end of the rotary pipe 5, to which it is coupled by a suitable rotary swivel 75. The power for driving the shaft 13 may be derived from a motor 76 located at one side of the derrick.

20 In the use of our invention the rotary pipe or drill spindle 5 is suspended by the cable 20 within the well through the pipe-chuck 10 and the opening 4 of the journal 3, and is lowered either by a loosening of the brake-band 44 on the drum, which permits a paying out of the cable 20, or by gravity action during the drilling operation. A rotary drilling movement is imparted to the rotary pipe or drilling spindle 5 from the shaft 13 25 through the drive pinion 12, when in clutch engagement with the shaft, the drive-sleeve 6, filler-ring 9 and rotary chuck 10, the chuck 10, both in its present embodiment and in the forms heretofore commonly used in rotary boring machines, permitting the rotary pipe or spindle 5 to feed downward therethrough by its own weight while having a rotary drilling movement imparted thereto by the chuck. The chuck 10 illustrated may 30 be released from driving engagement with the pipe at any time by a slight back turning movement of the driver-sleeve 6 and parts carried thereby, or the chuck rollers may be moved back to released positions by 35 hand after a slight back turning of the carrying parts to release the binding engagement of the rollers 9 with the pipe. When driving the rotary pipe 5, the drum driving pinions 23 and 24 are idle on the shaft, so 40 that no driving action can then be imparted to the draw-drum. When it is desired to withdraw the rotary pipe from the well, one or the other of the pinions 23, 24, depending 45 on the speed at which it is desired to drive the drum 15, is engaged to the shaft by a movement of its clutch and the drum is then 50 rotated to wind the cable 20 thereon and effect a consequent hoisting of the pipe. The control of the pinion clutches 14 and 26 is 55 effected through a single control lever 34, which may be engaged to the clutch bar 32 through the medium of the dog 36, by leaving the latch 39 in its normal position, or may be engaged to the clutch bar 33 through 60 the medium of said dog by drawing the latch 65

39 toward the lever, the dog then being held in such position by the trip rod shoulder 42 until such trip rod is moved by hand to released position.

During a driving of the drum 15 to wind 70 the draw cable thereon, the brake lever 49 is operated to release the holding engagement of the brake band 44 with the drum, and when the driving of the drum is stopped, the brake-band is operated to engage 75 and hold the drum against back turning thereof, as may be desired.

It is evident that we have provided a simple and efficient combined rotary boring 80 machine and draw works, the parts of which are arranged in compact form and driven from a common shaft.

The term "rotary pipe" where employed in the specification and claims will be understood to apply to the rotary tool carrying element which is usually hollow, in the form of a pipe, to permit the flow of water and drillings outward therethrough, but may comprise a spindle or other form of tool 90 carrying element, and is therefore not necessarily restricted to a pipe or hollow drill stem or spindle, strictly speaking.

We wish it understood that our invention is not limited to any specific construction, 95 arrangement or form of the parts as it is capable of numerous modifications without departing from the spirit of the claims.

Having thus described our invention, what we claim as new, and desire to secure by 100 Letters Patent is—

1. In a rotary boring machine, a rotary driver sleeve, a rotary-pipe drive chuck carried thereby, a draw-drum mounted around said sleeve for rotation relative thereto, and 105 bearing means for said sleeve.

2. In a rotary boring machine, a rotary-pipe driving means, a hollow vertical bearing for said means, and a draw-drum journaled on said driving means for rotation 110 relative thereto.

3. In a rotary boring machine, a rotary-pipe driving means, a hollow bearing for said means, a draw-drum journaled in an circling relation to said means, a drive shaft, 115 and means operable to connect said shaft with either of said driving means or drum, to drive the same.

4. In a rotary boring machine, a rotary-pipe driving means, a hollow bearing therefor, a draw-drum journaled on said means, means for imparting rotation to either said driving means or drum, and brake means for said drum.

5. In a machine of the class described, rotary drive means and a drum mounted for relative rotation and having registering work receiving openings therethrough, and means for selectively driving said drive means and drum.

6. In a rotary boring machine, a hollow vertical journal, a rotary-pipe driver and a draw-drum having parts telescoped for relative rotary movements and one mounted on 5 and carried by said journal.
7. In a rotary boring machine, a hollow vertical journal through which a rotary pipe may be projected, a rotary-pipe driver mounted on said journal, and a draw-drum 10 journaled on a part of said driver.
8. In a rotary boring machine, a hollow vertical journal, a rotary-pipe driver and a draw-drum carried by said journal for relative rotary movements, and means for imparting rotation to either said driver or 15 drum.
9. In a rotary boring machine, a hollow vertical journal, a rotary pipe driver and a draw-drum having parts telescoped for relative 20 rotary movements and one mounted on and carried by said journal, and means for imparting rotation to either said driver or drum.
10. In a rotary boring machine, a frame 25 having a part forming a hollow vertical bearing, a driver sleeve rotatable on said bearing, a rotary-pipe chuck carried by said sleeve in register with the bearing opening, means for driving said sleeve, and a draw- 30 drum mounted for rotary movements relative to said sleeve and substantially concentric therewith.
11. In a rotary boring machine, a frame 35 having a part forming a hollow vertical journal, a driver sleeve rotatable on said journal, a rotary-pipe chuck carried by said sleeve and driven thereby and in register with the journal opening, a draw-drum mounted for rotary movements relative to 40 said sleeve around the same, and means for driving said drum.
12. In a rotary boring machine, a frame 45 having a part forming a hollow vertical bearing, a driver rotatably carried by said bearing, a rotary-pipe chuck carried by said driver and driven thereby in register with the bearing opening, a draw-drum mounted for rotary movements relative to said driver around its axis, and means for driving either 50 the driver or drum.
13. In a rotary boring machine, a frame 55 having a part forming a hollow vertical journal, a driver sleeve rotatable on said journal, a rotary-pipe chuck carried by said sleeve and driven thereby and in register with the journal opening, a draw-drum mounted for rotary movements relative to 60 said sleeve around the same, and means for driving either said sleeve or drum.
14. In a machine of the class described, a rotary-pipe driver and a draw-drum sleeved one on the other for relative rotation, a bearing for said drum, and means for driving said driver at one speed and said drum at 65 a different speed.
15. In a machine of the class described, a driver and a draw-drum mounted for relative rotation about a common point, a bearing carrying said driver and drum and means for driving said driver at one speed 70 and said drum at a different speed.
16. In a machine of the class described, a frame having a part forming a hollow vertical journal, a rotary pipe driver and a draw-drum sleeved one on the other for relative rotation and one rotatably sleeved on 75 said journal, and means for driving either said driver or drum.
17. In a machine of the class described, a driver and a drum adapted to have relative 80 rotary movements about the axis of an object being driven, a bearing carrying said driver and drum, means for separately driving said driver and drum, and a brake band encircling a portion of said drum and operable 85 to resist rotation thereof.
18. In a machine of the class described, a hollow vertical journal, a driver sleeve rotatably mounted thereon, a rotary-pipe 90 chuck and a draw-drum carried by said sleeve, the latter only for rotation relative thereto, and means for separately driving said sleeve and drum.
19. In a machine of the class described, a hollow vertical journal, a driver rotatably 95 sleeved on said journal, a rotary-pipe chuck and a pipe clamping means carried by said driver for rotation therewith, a draw-drum mounted for rotation relative to said driver around the pipe being driven, and means 100 for separately driving said driver and drum.
20. In a machine of the class described, a hollow vertical journal, a rotary-pipe driver rotatably mounted on said journal and having an annular gear at its base portion, a draw-drum journaled on said driver and 105 having an annular gear on its lower portion, and means having drive pinions in mesh with said gears and selectively adaptable to be rendered active or idle. 110
21. In a machine of the class described, a rotary-pipe driver having an annular gear at one end, a draw-drum having an annular gear at one end, bearing means carrying said driver and drum, means having drive 115 pinions in mesh with said gears and selectively adaptable to be rendered active or idle, and a brake operable to resist a rotation of said drum.
22. In a machine of the class described, a hollow vertical journal, a rotary-pipe driver rotatably mounted on said journal and having an annular gear at its base portion, a draw-drum journaled on said driver and having a plurality of annular gears at its 120 lower portion, and drive means operable to selectively drive said gears.
23. In a machine of the class described, a rotary-pipe driver, a bearing for said driver, a draw-drum mounted for substantially con- 125
- 130

centric rotation on said driver and each having a gear, one within the other, a drive shaft at one end of said driver and drum, and means to place said shaft in driving connection with either of said gears.

24. In a machine of the class described, a driver sleeve and a draw-drum journaled to adapt them to have relative rotation around a common point, each having a gear 10 at its lower end concentric to its axis of rotation, a hollow bearing for said sleeve and drum, a pipe chuck carried by said sleeve, a drive shaft disposed below said driver and drum, means operable to place 15 the shaft in driving connection with either of the gears, and brake means for the drum.

25. In a machine of the class described, a frame, a driver sleeve and a draw-drum mounted on said frame for relative rotary 20 movements around a common line passing through the frame, said driver sleeve and drum each having a gear at its lower end, a chuck carried by said sleeve and means 25 carried by and removable as a unit from said frame below said driver and drum, and including a drive shaft, and means carried thereby and operable to place the shaft in driving connection with either of said gears.

30 26. In a machine of the class described, a frame having a hollow upright journal through which a rotary pipe may project, a driver rotatably sleeved on said journal and having a rotary pipe chuck at its upper end 35 and a gear at its lower end, a draw-drum rotatably carried by said driver and having a gear at its lower end without the driver gear, brake means for said drum and means removably suspended from said frame beneath 40 said driver and drum and including a drive shaft and means carried thereby and operable to place the shaft in drive connection with either of said gears.

27. In a machine of the class described, a 45 frame having a hollow upright journal through which a rotary-pipe may project, a driver rotatably sleeved on said journal and having a rotary-pipe chuck at its upper end and a gear at its lower end, a draw-drum rotatably carried by said driver and having a 50 plurality of gears at its lower end without the driver gear, brake means for said drum, and means removably suspended from said

frame below said driver and drum and including a drive shaft and means carried 55 thereby and operable to selectively place the shaft in driving connection with any of said gears.

28. In a machine of the class described, rotary-pipe driving means and a draw-drum mounted for relative rotation about a common axis, and each having a gear at one end, a drive shaft disposed at the geared 60 ends of said driving means and drum, and manually controlled means operable to selectively place the shaft in driving connection with either of said gears but not both 65 at one time.

29. In a machine of the class described, a bearing, a rotary driver and a drum carried 70 by said bearing for relative rotary movements around a common point, the driver having one end geared and the drum having a plurality of gears at one end, a drive shaft, and manually controlled means operable to selectively place said shaft in driving 75 connection with any one of said gears.

30. In a machine of the class described, a rotary driver, a chuck carried by said driver and comprising a body member having an opening therethrough axially of said driver, the wall of said opening having successive circumferentially extending cam surfaces, and chuck rollers mounted in said member 80 and coöperable with said cam surfaces to clutch an article projected through said opening when the driver is rotated in one direction.

31. In a machine of the class described, a rotary driver, a chuck carried by said driver 90 and comprising a body member having an opening therethrough axially of said driver, the wall of said opening having successive circumferentially extending cam surfaces and two pairs of clutch rollers mounted in 95 said member and coöperable with the cam surfaces to clutch an article projected through said opening when the driver is rotated in one direction, the rollers of each pair opposing each other and the rollers of one pair being shorter than those of the other.

In testimony whereof, we have hereunto signed our names.

HARRY R. NOFTZ.

FREDRICK J. SCHWIMMER.
